UNITED STATES PATENT OFFICE

149,947

DESIGN FOR A WHIRLIGIG

Paul Karakash, Eddystone, Pa.

Application June 20, 1946, Serial No. 130,882

Term of patent 3½ years

(Cl. D34—15)

To all whom it may concern:

Be it known that I, Paul Karakash, a citizen of the United States, residing at Eddystone, in the county of Delaware and State of Pennsylvania, have invented a new, original, and ornamental Design for a Whirligig, of which the following is a specification, reference being had to the accompanying drawing, forming part thereof.

Figure 1 is a side elevation of a whirligig, showing my new design, the same being partially broken away.

Figure 2 is a side elevation, taken in the direction of the arrow 2 in Figure 1.

Figure 3 is a top plan view of the whirligig illustrated in Figures 1 and 2, and

Figure 4 is a cross-sectional view, taken in the plane of the line 4—4 in Figure 3.

I claim:

The ornamental design for a whirligig, as shown.

PAUL KARAKASH.
